(57) **CLAIM**

The ornamental design for an electrical connector, as shown and described.

DESCRIPTION

FIG. 1 is a perspective view of a first embodiment of an electrical connector showing our new design with the male connector coupled to the female connector;

FIG. 2 is a perspective view of the male connector thereof, the female connector being omitted for ease of illustration;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a front-top perspective view of the female connector thereof, the male connector being omitted for ease of illustration;

FIG. 10 is a front-bottom perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The short dash-short dash lines illustrate portions of the electrical connector that form no part of the claim. The long dash-short dash lines in the figures represent the unclaimed boundary of the design.
